INFANT INCUBATOR

George H. Stoner, Hatboro, Pa., assignor to Air-Shields, Inc., Hatboro, Pa., a corporation of Delaware
Filed May 12, 1959, Ser. No. 812,658
32 Claims. (Cl. 128—1)

This invention relates to an infant incubator, and, more specifically, to an incubator incorporating a number of special features which result in a combination construction having a number of advantages from the standpoint of the comfort, health and safety of the occupant.

Various prior art structures involve an enclosed occupant space, means for forcing air circulation through the occupant space, various controls for affecting the temperature, moisture and oxygen content of the air going through the occupant space, and various other general features which are common to such prior devices and the structure of the present invention. However, the present invention incorporates a number of special features which give rise to an overall combination having distinct advantages over any possessed by the various prior devices.

An important object of the invention is the provision of an incubator having a highly refined degree of control over the temperature, moisture and oxygen content of the air flowing through the occupant space while at the same time being capable of easy and quick partial disassembly for inspection and cleaning and providing specially constructed pieces to facilitate cleaning operations.

Another object of the invention is the provision of a specially shaped and formed base having an arrangement of air chambers susceptible to complete and quick cleaning from a convenient working position above the base.

Still further, the invention has as an object the provision of an air humidifying and an air cooling chamber, which two chambers are inserted in the air flow circuit in parallel so as to provide a degree and sensitivity of temperature and moisture control not heretofore possible.

Yet another object of the invention is the provision, in equipment of the kind described, of a unitary sub-assembly of working parts capable of quick and easy removal from the incubator for ease of inspection and maintenance. In connection with this object it is pointed out that the invention includes a specially constructed fan having a housing cast as a smooth-walled part of the base member and having an impeller readily removable from the base so as to facilitate cleaning thereof.

Further objects of the invention include the provision of a special filter adapted to effect a vigorous filtering action on air coming into the incubator whereby to guard against the importation into the unit of various airborne pathogens; the provision of a humidifying chamber having a simple and efficient combined intake port, level indicator and drain device; and the provision of a new type of gasket for use in sealing between the cover and base, which gasket is readily removable for cleaning.

Other objects and advantages of the invention will be clear from the following description taken together with the accompanying drawings in which:

FIGURE 1 is a front elevation, partly in section, of an incubator according to the invention, the part in section being taken generally along the line 1, 1 of FIGURE 2;

FIGURE 2 is a top sectional view taken generally along the line 2, 2 of FIGURE 1;

2

FIGURE 3 is a cross-sectional view, partly broken away, taken generally along the line 3, 3 of FIGURE 1 and on an enlarged scale as compared to FIGURE 1;

FIGURE 4 is a fragmentary cross-sectional view taken generally along the line 4, 4 of FIGURE 1;

FIGURE 5 is a perspective view, on a reduced scale, looking downwardly toward the rear of an incubator according to the invention, this view showing the cover and humidity control device in phantom outline by dot-and-dash lines;

FIGURE 6 is an exploded sectional view showing the incubator base in cross-section and the removable sub-assembly in position for assembly into the base; and

FIGURE 7 is a fragmentary cross-section illustrating an adapter for the filter as seen in FIGURE 3.

Referring to the drawings in more detail, a general description of the main parts of the invention will first be given. The incubator base B supports a deck D and cover or hood C, the deck and cover together forming an enclosed occupant space S. A mattress M rests on the deck D within the occupant space S and is adapted to receive an infant placed in the incubator.

The incubator of the invention is adapted to rest on a table or shelf in a hospital nursery, or, preferably, to rest on a cart mounted on casters to facilitate movement of the incubator to any convenient position in the hospital nursery.

Forced air circulation is provided by a fan F located below the deck D, which fan forces air to pass through a plurality of chambers below the deck D and thereafter to pass through the humidity control device H and into the occupant space. After circulating through the occupant space, the air is returned to the region below the deck D through the return duct R and is then recycled and mixed with a proportion of fresh air drawn in through the filter FR and, when oxygen is being used, a proportion of oxygen taken in through the oxygen supply line O. While passing through the various chambers below the deck D, the air is subjected to a number of treatments in order to adjust its temperature, moisture content and oxygen content.

Convenient access to the infant, with a minimum of exposure of the infant to outside air, is provided for by means of the access port AP and iris-ports IP.

Attention is now turned to a more detailed description of the structure of the invention.

The base B comprises a front side wall 9, rear side wall 10, end walls 11 and 12, and bottom flange 8 formed by bending inwardly the bottom edges of the front, rear, and end walls. As best seen in FIGURE 1, the walls 8 to 12 form an upwardly open housing within which various other parts of the base are located.

The top edges of the side walls 9 and 10 and the end walls 11 and 12 are bent over, downwardly, and inwardly as shown at 13 to form a flat flange running around the inside of the housing and adapted to support the main base member 14 which preferably rests against a gasket 15 running all the way around the unit.

As seen in FIGURE 3, the cover C is fixed to the base B by means of an elongated or piano-type hinge 16 running substantially along the entire top edge of the back side wall 10. The cover can thus be displaced from its downward or closed position, as illustrated, by tilting the cover upwardly and backwardly on the hinge 16. Such action permits access to the occupant space for the insertion and removal of an infant into and from the incubator.

The base or housing member 14, as best seen in FIG-

URE 5, is formed as a unitary, smooth-walled casting or molding extending over the entire area of the incubator. This construction is of special significance and importance. Heretofore, incubators have involved relatively complex base structures having tortuous air flow passages, some of which were internal within the structure of the base, some of which included rubber hoses or other pipe members, and some of which were covered by separate plates welded or screwed into place. Such structures, in addition to being relatively complicated to manufacture, result in a structure which can be disassembled only with considerable effort and nuisance. It thus follows that, as a practical matter, the base of such a prior-type incubator is not thoroughly cleaned and sterilized except only at quite infrequent occasions.

In contrast with such prior types of base structures, the unitary casting of the invention has a series of simple, upwardly open depressions or chambers in the top surface thereof and this type of structure yields itself to quick and easy exposure by removal of the top deck D and quick and thorough cleaning or sterilization.

A number of separate chambers or depressions are preferably provided in the unitary base member 14, the structure illustrated in the drawings including a mixing chamber 17, a heating chamber 18, a dry-air or cooling chamber 19, and a humidifying chamber 20. As clearly seen in FIGURE 5, these chambers are substantially rectangular in plan and arranged in side-by-side relation so as to occupy virtually all of the top surface of the base 14. Several integrally cast walls serve to divide the chambers one from another. Thus, wall 21 separates the mixing chamber 17 from the heating chamber 18, wall 22 separates the heating chamber 18 from the dry-air and the humidifying chambers 19 and 20, and wall 23 separates the dry-air or cooling chamber 19 from the humidifying chamber 20.

The base casting 14 also includes certain integral passage means interconnecting the various air flow chambers. Air passes from the mixing chamber into the heating chamber via the impeller housing 24 (see FIGURES 1 and 3) which opens into chamber 18 at 25. Chamber 18 is interconnected with chambers 19 and 20 by means of a break in wall 22 as shown at 26 and chambers 19 and 20 are interconnected with each other because of a break in wall 23 as shown at 27.

The heating chamber 18 includes a heater element 28 which, in the form illustrated, is a loop of tubular material in which an electrical resistance wire is arranged. Heating chamber 18 also includes an auxiliary cover plate 29 which rests along one edge on shoulder portion 30 and, at the opposite edge, on pin 31 protruding from the wall of the chamber. The auxiliary plate 29 serves to minimize the chance of the development of a hot spot in the mattress M immediately above the heating element 28. However, it is noted that the plate 29 merely rests in place without any special attachment means and it can thus be easily manually lifted off when it is desired to scrub out and sterilize the heating chamber.

The dry-air or cooling chamber 19, as best seen in FIGURES 1, 2 and 4, is located directly above an ice chamber 32. The ice chamber 32 is formed by the dependent housing member 33 secured to the underside of the base casting in any convenient manner, such as by means of the bolts 34 cooperating with tapped holes 35.

The underside of the dry-air or cooling chamber 19 includes an elongated keel member 36 and a plurality of transverse web members 37 which protrude downwardly into the ice chamber 32. When temperature conditions around the incubator are such that cooling is needed to provide air at a desired temperature for the occupant space, the keel and web members facilitate the dissipation of heat from the cooling chamber 19 into the ice and cold water which may be maintained in the ice chamber 32.

A covering of insulation material 38 is provided

around the walls 33 of the ice chamber so as to minimize the transfer of heat to the ice chamber from any direction other than the chamber 19 and to prevent condensation dripping.

5 The end wall 12 of the incubator base is apertured opposite the end of the ice chamber 32 and a hopper member 39 is provided, together with a lid 40 hinged as at 41 and a drain pipe 42 having a stock cock 43 so as to make possible the insertion of crushed ice or ice cubes 10 and cool water into the ice chamber 32 and the removal of warmed water from that chamber.

The humidifying chamber 20 is provided with a combined fill pipe, level indicator, and drain indicated generally at 44 in FIGURES 2 and 4. Thus, a pipe 45, 15 threaded on the end as at 46, is screwed into a tapped aperture 47 passing through the wall 48 of the humidifying chamber 20. It is noted that the bottom wall 49 of this chamber slopes toward the front of the unit, that is, toward the side on which the connection with the pipe 45 20 occurs. In addition, as seen in FIGURE 1, the wall 49 slopes downwardly toward the right, the net result of the double slope of the wall 49 being the connection of the pipe 45 with the chamber 20 at the lowest point in the chamber. The pipe 45 extends outwardly through the 25 front wall 9 of the incubator base and terminates in the threaded portion 50. A tubular member 51 is provided with a correspondingly threaded aperture 52 so as to be screwed into position on the end of pipe 45. The tubular member 51 is open at one end, except for a spring 30 snap-cover 53 and closed at the other end as indicated at 54. Packing means 55 is provided to minimize leakage between the tubular member 51 and the pipe 45.

When the tubular member 51 is in the upright position (shown in FIGURE 4), the water may be fed into 35 the humidifying chamber 20 by manually lifting the snap-cover 53 and pouring the water into the open end of tubular member 51 from which it flows through pipe 45 to the chamber 20. In this position the tubular member 51 also serves as a level indicator, conveniently by means 40 of a transparent portion included in the front wall.

When it is desired to drain the water out of the humidifying chamber 20, the tubular member 51 is rotated 180° on the pipe 45 to a position in which it extends downwardly and, of course, in this position the water is 45 free to run out of chamber 20 through pipe 45 and out through the tubular member 51.

Attention is here called to an important aspect of the invention. The cooling chamber 19 and the humidifying chamber 20 are arranged in the air flow circuit in parallel rather than in series. This is accomplished, in 50 part, by means of the relative positioning of the separation walls 22 and 23 which makes possible a flow of air from the heating chamber into either the chamber 19 or the chamber 20 or both chambers. The control of the 55 proportion of air passing through each of chambers 19 and 20 is accomplished by means of the delivery member or humidity chute H to be described in more detail herebelow. The arrangement of the chambers 19 and 20 in parallel makes possible a nicety of control of air conditions not heretofore possible. In various prior devices air passed from the heating chamber through the cooling chamber and then either directly into the occupant space or through a humidifying chamber and into the occupant space. Thus, if it were desired to both cool and humidify 60 the air, it was first necessary to cool the air and thereafter humidify it. However, this arrangement has the distinct disadvantage that cooler air does not absorb moisture nearly as rapidly as warmer air. With the arrangement of the invention, however, it is possible to pass a portion of the warmer air over the water in the humidifying chamber and humidify it under the most advantageous circumstances, while passing another portion of the air through the cooling chamber with the result that the 65 subsequent mixture of air has been efficiently cooled and humidified.

It is here mentioned that positive cooling action by means of ice and cold water in the chamber 32 is needed only occasionally in most hospitals. Of course, the frequency of the need for cooling action depends to a large extent on the climate prevailing at the location of the hospital. In the north temperate climate, in a hospital which is not provided with central air conditioning, it is usually only necessary to provide positive cooling action for a total of about a week or two during the course of a year. Periods when cooling action is needed occur when the hospital temperature rises to 90-92° F. and the desired temperature inside the incubator is about 95° F. Under such conditions, because of the heat necessarily added to the atmosphere within the incubator by the body of the infant and the various electric components (even without the heater element), there is a tendency for the atmosphere within the incubator to rise in temperature to an extent which may be detrimental to the health of the infant.

In particularly hot climates it may be necessary to use ice in the ice chamber for three or four weeks out of the year, or perhaps even more.

However, notwithstanding the fact that positive cooling action is ordinarily used for only a relatively small fraction of the year, it is vitally important to have fully equipped and controlled provision in the incubator for adequate cooling action. The prevention of excessive temperatures can save the lives of premature infants.

During times when it is not necessary to provide positive cooling action and there is, therefore, no ice or cold water in the ice chamber, the chamber 19 acts as a dry-air chamber or duct. Adjustment of the humidity chute H can thus effect a feed of more air or less air through the humidifying chamber and accurately control the relative humidity of the occupant space.

During periods when ice and cold water are loaded into the ice chamber 32, there tends to be a generalized cooling effect because of the thermal conductivity of the unitary base casting. The ice tends to cool more than just the floor and walls of the cooling chamber 19. Specifically, portions of the floor and walls of the heating chamber 18, such as the inclined portion best seen in FIGURE 1, are cooled. This generalized cooling action is desirable because it makes possible the combination of substantial cooling action at the same time as substantial humidifying action. This is done by sliding the humidity chute well over toward the right (as viewed in FIGURE 4). There is some cooling action on the air even if the humidity chute is all the way over to the maximum humidity position because the air will come in contact with various cooled portions of the unitary casting even though it does not flow directly through the cooling chamber and into the occupant space but instead flows through the humidifying chamber into the occupant space.

The deck member D is substantially coextensive with the base casting 14 and thus serves to close off the top of each of the chambers 17 to 20 arranged in the base member. The deck member D includes an upturned flange 56 around the periphery thereof which aids in positioning the deck inside of the gasket member 57, described more fully herebelow, on which cover C rests. The deck member includes a pair of spaced apertures 58 and 59, the aperture 58 communicating with the dry-air or cooling chamber 19 and the aperture 59 communicating with the humidifying chamber 20. In addition, the deck includes an elongated aperture 60 at the opposite end thereof through which air passes from the occupant space downwardly to the chambers below the deck. A shield member 61 is advantageously secured to the bottom surface of the deck, for instance by means of screws, such as 62, in position around the aperture 60. The mattress M is carried on auxiliary support plate 63 which, in turn, is supported on deck D by means of downturned flanges 64 which are spaced around the periphery of the

support plate 63. The flanges 64 hold the mattress up off the deck and thus provide an insulating air space to guard against the possibility of hot spots on the mattress. The support plate also includes a number of upturned flanges 65 which serve to retain the mattress M in position on the support plate 63.

Cross plates 66 and 67 (see FIGURE 1), are arranged in the incubator at opposite ends thereof and may be secured in place by means of screws, such as those shown at 68, passing through cover C. The cross plates 66 and 67 confine the longitudinal motion of an infant in the incubator and prevent the infant from interfering with the free flow of air into or out of the incubator. For this purpose, the upper edges of the cross plates 66 and 67 must be high enough above the mattress to guard against the possibility of the infant's head resting on or partly on, the upper edge of one of the cross plates. It is thus necessary to have the top edge of the cross plate at least above the midpoint of the infant's skull, when measured vertically from the mattress surface. In other words, it is necessary for the cross plates to be high enough so that the top of the infant's head will contact the flat face of a plate rather than riding partially up over the plate and resting on the edge.

In addition to confining the longitudinal motion of the infant, the cross plates 66 and 67 act as baffles and minimize direct drafts across the mattress. They also can serve as support means for either end of the mattress support plate 63. Thus, as indicated in dot-and-dash lines in FIGURE 1, the mattress and support plate may be tilted upwardly at one end in order to place the infant resting on the mattress in a position to facilitate breathing.

Attention is now turned to the details of the humidity chute or delivery member H. As seen in FIGURES 1, 2 and 4, the delivery member includes a support member 75 adapted to rest on top of the deck D. The support member 75 includes a cut-out portion 76 along one edge thereof adapted to cooperate with pins 77a, 77b so as to limit travel of the humidity chute across the surface of the deck D. An upstanding hollow chute 78 is provided extending upwardly from the support member 75. The wall of the chute member 78 adjacent the end of the cover C is curved inwardly as at 79 to provide a guide tending to direct the stream of air flowing upwardly through the hollow member 78 in an upwardly and inwardly direction in the occupant space. The opposite side 80 of the hollow member 78 is shorter than side 79 to provide an exit opening 81 through which the air may pass. The delivery member also includes baffles 82, and 83 to aid in the complete mixing of the air as it passes through the delivery member and to minimize the chance of the formation of excessive drafts within the occupant space.

The support member 75 includes an elongated aperture 84 communicating with the inside of the hollow member 78.

The spacing of the pins 77a and 77b and the dimensions of the hollow member 78 are arranged, with respect to the spacing and size of the holes 58 and 59, so that, when the delivery member is shifted toward the left, as viewed in FIGURE 4, as far as the cutout 76 and pin 77a will permit, the aperture 58 leading to the dry-air or cooling chamber will be in communication with the interior of the delivery member while most of the aperture 59 is covered by the end of the support member 75. Because of the importance of adequate moisture in the atmosphere within the incubator, the pin 77a is positioned so that the hole 59 over the humidifying chamber is not completely closed off in any position of adjustment. This is an important safety feature of the invention. Conversely, when the delivery member is shifted all the way to the right, as viewed in FIGURE 4, the hollow member will communicate with the humidifying chamber 20 through the hole 59 while the other end of the support member 75 occludes the passage 58 leading to the dry-air

or cooling chamber 19. It will be seen that the proportion of air flowing through the delivery member from the chamber 19 and from the chamber 20 can be accurately controlled by selecting the position of the delivery member with respect to the wall 23 dividing chamber 19 from chamber 20.

The invention provides a special simplified control for shifting the delivery member H without necessitating opening of the cover C or even of an iris port IP. This is accomplished by means of a control knob 35 mounted for rotation with a shaft 36 that passes through the wall of the cover as at 37 and includes, on the end within the occupant space, a finger member 38 which is also fixed for rotation with the shaft. Collar member 39 surrounding the shaft outside of the occupant space includes a spring (not shown) tending to bias the assembly of shaft 36, control knob 35 and finger 38 toward the outboard position, that is, toward the left as viewed in FIGURE 1. The delivery member includes a pin or abutment means 90 adapted to cooperate with the finger 38. When the finger, shaft and control knob are in the left-hand position, as shown in FIGURE 1, rotation of the knob and other parts will not change the position of the delivery member because the finger 38 will swing clear of the pin 90. However, when the knob, shaft and finger assembly is manually axially displaced toward the right, as viewed in FIGURE 1, the finger 38 enters a plane parallel to the plane of motion of the delivery member, as limited by the engagement of the cutout portion 76 with the pins 77, such that the finger 38, upon rotation, will contact the pin 90 and effect motion of the delivery member. It will be seen that displacement of the delivery member in either direction is possible by means of the control knob and finger assembly since the finger can be, by means of simple manual manipulation, placed so as to engage the pin on either one side or the other.

The outboard surface of the wall 78 of the delivery member can conveniently include position indicating means as shown in FIGURE 4. As illustrated, five positions of the delivery device are included ranging from "min" standing for minimum humidity at the right, to "full" standing for full or maximum humidity at the left, the intermediate positions indicated being, from right to left, "50-65" or 50 to 65% relative humidity, "65-80" or 65 to 80% relative humidity, and "80-95" or 80 to 95% relative humidity. The delivery member can, of course, be positioned so as to deliver air at a humidity value between those specifically indicated on the back. Since the shaft on which the finger and knob are mounted remains in a central position regardless of the position of the delivery member, it is a convenient visual reference point by which to determine the position of the delivery member as indicated by the index on the back thereof.

The proportions and arrangement of the various parts of the humidity chute are especially significant. When properly selected, the humidity chute can perform a number of important functions in a manner to provide for the maximum safety and comfort of the occupant.

In the first place, the humidity chute must be designed so as to guard against hot spots above the mattress which might occur if a direct stream of hot air flowed regularly against one spot. The region of the occupant space from the surface of the mattress up to about 6" above the mattress must be substantially free from any hot spots. The temperature range over the mattress area should not exceed 3° F.

The humidity chute must be arranged, with respect to the position of the indicating thermometer 142, so that the thermometer accurately and consistently indicates the average temperature of the air in the region immediately above the surface of the mattress.

Perhaps most importantly, the humidity chute must deliver a stream of air into the occupant space in such a way as to insure adequate circulation to all parts of the space without involving air motion at a rate greater than

about 25 ft./min. in the region occupied by the infant, that is, the region extending up to about 4"-6" above the surface of the mattress. Air motion in excess of 25 ft./min. tends to give infants colds, even if the air is warm.

5 The baffles within the humidity chute must be arranged so as to set up sufficient turbulence in the stream of air passing through the chute to insure thorough mixing before the air is delivered to the occupant space. The free, or flow, area past each baffle is advantageously at least equal to the flow area up through the deck. Interposing restrictions in the humidity chute by utilizing a flow area past the baffles which is less than the flow area through the deck may result in an undesirable back pressure which, if excessive, can interfere with the intake of fresh air through the filter. In effect, the baffles within the humidity chute form a mixing chamber in which the air stream is thoroughly mixed during passage into the occupant space.

20 In order to accomplish delivery of the stream of air into the occupant space in the desired direction, the effective delivery opening, coupled with appropriate air flow guide means, is conveniently located above the upper edge of the cross plate 66. In the embodiment illustrated in the drawings, this is accomplished by extending the humidity chute upwardly a distance sufficient to present a delivery opening just above the upper edge of the cross plate 66. On the other hand, the effective delivery opening should not be more than about half way between the surface of the mattress and the roof of the cover.

25 Locating the effective delivery opening above the midpoint tends to result in an air stream bouncing off of the roof of the cover in a manner which sets up turbulence in the occupant space that results in an air flow across the surface of the mattress in excess of 25 ft./min.

30 35 The humidity chute should also deliver the air stream into the occupant space at an angle and height such as to make the upper portion of the occupant space, that is, the portion more than 4"-6" above the mattress, a mixing chamber in which the incoming air and the air already in the occupant space are thoroughly mixed, with all remote portions of the occupant space constantly swept clean of stale air. At the same time, as before mentioned, excessive turbulence and air flow in the region just above the mattress should be avoided.

40 45 I have found that a humidity chute proportioned and arranged like that illustrated in the drawings accomplishes all of the foregoing purposes with marked success.

Attention is now turned to the arrangement of the parts in the mixing chamber 17. As mentioned above, the mixing chamber 17 includes an integrally cast housing wall 24 surrounding the fan impeller 91 mounted for rotation with the motor shaft 92 protruding from the electric motor 93.

50 55 Impeller housing 24 is apertured as at 94 to provide for the ingress of air from the mixing chamber 17. In addition, a pipe member 95 having a terminal collar 96 in which a flared exit mouth 97 is arranged, extends from the region just inside of the aperture 94 (see FIGURE 3) outwardly through the wall of the chamber 17 through an aperture 98 provided with a grommet 99. The outboard end of the pipe member 95 is threaded as at 100 to cooperate with the threads 101 of an aperture in the filter housing 102.

60 65 The filter comprises a cap structure 103 provided with a plurality of apertures 104 through which outside air may pass into the interior of the filter. The periphery of the cap structure 103 is bent inwardly as at 105 and then outwardly as at 106 to form a peripheral flange. The filter housing 102 includes a corresponding shoulder 107. The shoulder 107 and flange 106 cooperate in squeezing therebetween the edge portion 108 of a piece of suitable filter material 109.

70 75 The cap structure 103 includes a central shaft 110 on which a cross bar 111 is mounted for rotation. The cross bar (see FIGURE 5) can be swung so that its end por-

tions slip under the heads of stop means 112 and 113 protruding outwardly from the filter housing 102. Thereafter the squeezing action of the cap structure against the filter material 109 can be increased by rotating the knurled knob 114 so as to advance the screw 115 and press screw shoulder 116 against the center of the bar 111.

The cap 103 is advantageously made of transparent material, such as clear plastic, to facilitate inspection of the filter. As the filter is used, it tends to darken in color because of the retained dirt taken out of the air. With the cap 103 transparent, a simple visual check determines if the filter should be changed. It is thus not necessary to shut the incubator down or take anything apart to check the filter.

By selection of a suitable filter material such as finely divided glass fibers or "glass wool," it is possible by means of the filter of the invention to remove substantially 100% of all of the particles in the air passing through the filter down to a particle size of 0.5 micron. Such filtering action yields air which is substantially completely free of pathogens and other contaminants. Such material also has the advantage of an exceptionally low 20 resistance to air flow.

After passing through the holes 104 and the filter material 109, air flows through the pipe 95 and into the impeller housing 24 where it is mixed with the air taken in from the mixing chamber 17 and delivered by the fan impeller to the heating chamber 18. It is noted that the aperture 94 in the housing 24 is substantially larger than the outside diameter of the collar member 96 on the 25 end of pipe 95. This provides an annular-shaped passage for the inflow of air from the mixing chamber into the impeller housing. Furthermore, the rush of air through this annular passage creates a suction force tending to pull air in through the pipe 95.

When an atmosphere rich in oxygen is to be used in the incubator, oxygen is fed into the mixing chamber 17 through the oxygen flow limiting device 117 associated with a source of oxygen indicated at O, which may take the form of a pressure tank of oxygen. From the oxygen flow limiting device 117 the oxygen flows through 40 pipe 118 into the mixing chamber 17.

FIGURE 7 illustrates an alternative embodiment in which the filter cap structure 103 is replaced by an adapter 119 which includes coupling member 120 adapted for connection to pipe 121 leading outside of the hospital. By this alternative embodiment fresh, outside air may be drawn into the incubator. The modified structure also provides air filter 122 to take out dust and other relatively large particles.

The mixing chamber 17 also includes important control apparatus. Thus, as best seen in FIGURE 3, a gas filled adjustable thermostat 123 and a fixed point thermostat 124 protrude into the mixing chamber 17. As seen in FIGURE 1, these two thermostats are surrounded by the shield member 61 secured to the bottom of the deck D and it thus results that the air flowing from the occupant space into the mixing chamber all passes directly over the two thermostats.

The adjustable thermostat 123 is connected by means of the capillary tube 125 to a bellows and plunger arrangement 126 having a control knob 127 protruding out the front of the incubator. By this control hook-up it is possible to adjust the thermostat so that it will control the heater element 28 in the heating chamber 18 (via the relay indicated at 128 in FIGURE 2) so as to turn the heater on when the temperature of the air returning from the occupant space falls below a desired value and turn the heater off when the air temperature exceeds a desired value.

The fixed point thermostat is set to override any control impulses received from the adjustable thermostat and positively turn off the heater 28 when the temperature returning from the occupant space exceeds a safe level. The fixed point thermostat, or safety thermostat, additionally

can be connected in one or more electric circuits so as to actuate various signal devices such as a red light on the control panel, a buzzer, a remote light at the nurses' station, etc. When an increase in the temperature occurs 5 below the deck, for instance when a garment, etc. partially blocks the return air passage, the safety thermostat will not only turn off the heater element but will also turn on the red light, buzzer, etc. and call the attention of the attendant to the fact that the temperature below the occupant space is rising. This control response occurs even when the conditions are such that the indicating thermometer 142 did not yet indicate to the attendant that there was anything amiss.

The thermostats 123 and 124, the heater 28, the motor 15 93 and impeller 91 are all mounted on a common motor board 129 (see FIGURE 3) and are thus adapted to be removed from the incubator as a unit in the manner indicated in the exploded view of FIGURE 6. This arrangement makes possible quick and easy access to all of the electric and control components for ease of maintenance and to facilitate cleaning. It is here mentioned that, as 20 seen in FIGURE 2, electric power is supplied to the unit by means of the cable 130 terminating in an elongated plug member 131 interfitting with plug member 132 fixed to the removable sub-assembly indicated generally at 133. With this arrangement, when it is desired to remove the sub-assembly 133, the plug 131 can be simply pulled out and this makes possible the removal of the sub-assembly 30 without any complicating interconnected wires remaining between the sub-assembly and the incubator.

The front of the sub-assembly 133 is provided with a control panel 134 on which the knob 127, already mentioned, is mounted. There are a number of additional control and indicating knobs and lights included on the 35 control panel. Thus, as seen in FIGURE 2, there is provided a light 135 which turns on every time the heater element 28 is on and off when the heater is off. There is also included a light 136 which merely indicates the condition of the entire apparatus, that is, either power on or power off and a safety alarm light 137 which goes on only when the overriding or fixed point thermostat 124 takes control of the operation of the heater element.

The sub-assembly 133 is secured in position against the gasket 150 by means of the screws 138 indicated in FIGURE 6.

45 In connection with the cast base member 14 it is noted that all of the corners are either rounded as indicated at 139 or filleted as at 140 in FIGURE 2. This provides a smooth construction without intricate corners which greatly facilitates sterilization.

50 Mention has already been made of the gasket member 57 sealing the cover C to the base B. This gasket 57 (as seen in FIGURE 4) is of special construction. In prior constructions, the cover has been sealed against the base by means of a strip of rubber cemented to the base. However, this results in a number of disadvantages. In the first place, the rubber gasket gradually wears out and it is then difficult to scrape it off and install a new one. In the second place, the gasket becomes contaminated but does not lend itself to ready and complete sterilization. 55 The gasket 57 of the invention is of a new type. In the first place it is noted that it is made of a smooth and non-sticky or non-gummy plastic material which is easy to wipe clean or sterilize. In the second place, it is noted that the gasket is not in any way cemented or sealed in place. It merely rests upon the base member and can thus be picked up when it is desired to clean the unit. It is also noted that the gasket 57 is in the form of a flattened tube having a hollow interior 141. This construction 60 yields a particularly flexible gasket capable of insuring good sealing action between the cover and base notwithstanding possible irregularities or warping of one member or the other, because the air sealed in the hollow portion 65 141 is readily compressible to accommodate portions of the periphery where the fit between the cover and base

is relatively tight. At the same time, the gasket is of substantial thickness to effectively seal those portions of the periphery where the cover and base are relatively far apart.

In the upper right-hand corner of the incubator, as viewed in FIGURE 1, there is provided a safety thermometer 142 inside of the unit. This thermometer can be observed by the attendant from outside of the incubator and serves as a double check on the temperature inside of the unit. The thermometer 142 is mounted in a special mounting device 143 which, by means of the insulation chamber 144 (see FIGURE 3) guards against the fogging over of the instrument mount in a manner which would impair the visibility of the thermometer from outside the unit.

The iris-ports IP, two of which are provided in the front of the cover and two in the rear of the cover, make possible easy access to the infant in the incubator without opening the entire cover C.

A hook device 145 may be provided in the top of the unit, as shown in FIGURE 1, to make possible a weighing of the infant without removal from the incubator. This is done by placing a scale on top of the unit in connection with the top of the hook member and by hanging the infant in a sling from the bottom of the hook member.

Small vents 146 are provided, it being understood that air normally flows outwardly through these vents because of the slight positive air pressure within the incubator. The constant bleed-off of air through the vents 146 and the intake of air through the filter FR provide for freshening of the atmosphere within the incubator.

A handle 147 is provided on the deck member D adjacent the return chute R. This handle may be secured in position by means of the screws 148. As seen in FIGURES 1 and 3, the handle is in a position to minimize the chance that objects, such as a diaper, blanket, etc. will obscure the return air duct. The handle will hold such an object out of tight contact across the return duct and also provide, by means of the hollow portion 149 beneath the handle for an auxiliary channel through which the air can flow into the return chute in the event that the upwardly open aperture 60 is partially blocked.

The gasket 15 between the base casting and base housing and the gasket 150 between the removable motor board assembly and the base casting together perform an important function. Safety requirements, as set forth by the Underwriters' Laboratories, specify that, in any device employing an oxygen-rich atmosphere, the motor and other electrical components must be separated and sealed from the oxygen-rich space. The two gaskets mentioned provide the sealing action required. In addition, the seals act as a thermal barrier when the chamber 19 is acting as a cooling chamber and prevent the direct conduction of heat from the casing to the base casting, from which such heat would have to be withdrawn by means of the ice below the cooling chamber.

With all of the foregoing structural description in mind, attention is now turned to the operation of the incubator of the invention.

Initially, the incubator fan is turned on, which will be indicated by the lighting up of bulb 136, and the temperature control 127 on the control panel is adjusted so as to place the heater element in constant operation. This will result in lighting the bulb 135. The incubator should be operated in this condition for about an hour or more in order to pre-heat all of the parts to the desired operating temperature before an infant is placed in the occupant space.

Periodic checking of the temperature indicated on the indicating thermometer 142 will enable the operator to determine when the incubator has warmed up to the desired level. When this point is reached, the heater control knob 127 is turned down just far enough to turn the heater off, this condition being indicated by the turning off of the indicating light 135. The adjustable ther-

mostat 123 is, in this fashion, adjusted so that, from then on, the unit will operate automatically to turn the heater on when the temperature falls below the desired level and to turn the heater off when the temperature tends to rise above the desired level.

During the warm-up period, the humidifying chamber 20 should be filled with water, this being accomplished by rotating the fill pipe 44 to upright position, displacing the cap 53, and pouring water into the upstanding hollow member. The humidity control knob 85 is then manipulated so as to move the humidity chute into the position which will give the desired degree of relative humidity.

The iris-ports IP and the access port AP should be closed.

When it is desired to enrich the oxygen content of the atmosphere within the occupant space, the oxygen supply line O is connected to a source of pressure oxygen which is then turned on to permit oxygen to flow through the oxygen flow limiting device 117 and into the mixing chamber 17.

When it is desired to draw in air from the hospital nursery, a fresh piece of filter material is clamped into position in the filter FR. In the alternative, when it is desired to take in fresh outside air, the parts shown in FIGURE 7 should be substituted for the filter parts (for instance as shown in FIGURE 3) and the hose or pipe 121 connected to a source of outside air.

After the initial startup period, the desired conditions of temperature, humidity, and oxygen content will stabilize within the occupant space.

An infant is placed in the incubator by tilting the cover C backwardly and resting the infant on the mattress M. When desired, an end of the mattress can be propped up, for example to facilitate breathing. With the infant in position on the mattress, the cover C is rocked forwardly and downwardly to the closed position. Thereafter, changes in the temperature level or relative humidity within the occupant space can be effected from outside of the unit by manipulating the control knobs 127 and 85.

In tropical climates or during a summer heat wave, the temperature of a nursery may exceed that desired inside of the infant incubator. When this occurs, cooling rather than warming of the air in the occupant space is required to maintain optimal temperature for the infant. This is accomplished by filling the ice chamber 32 with ice and cold water through the hopper member 39. It is usually desirable when cooling the air in the occupant space to provide a high degree of humidification and this is accomplished by shifting the humidity chute to the desired position. When the minimum desired temperature has been reached, as a result of the cooling action, the heater control knob 127 is turned just enough to turn on the heater which will be indicated by the light 135. Thereafter the adjustable thermostat will prevent overcooling by turning on the heater element whenever the temperature falls to the minimum desired level.

In the event that the temperature within the occupant space becomes excessive for any reason, the fixed point thermostat 124 will operate to shut off the heater, notwithstanding the condition of the adjustable thermostat, and turn on the warning signals, such as the light 137, buzzer, etc.

The heating capacity of the heater element must be adequate to maintain a stable minimum temperature of not less than 84° F. under the coldest nursery conditions (for example, 60°-65° F.), and, if outside air is used, the heating element must have the heating capacity to maintain the minimum temperature even when the outside air is as low as -20° F. The control thermostat must be sufficiently accurate and sensitive to maintain the desired temperature within ± 1 ° F.

The cooling capacity must be adequate to maintain

the incubator temperature at not more than about 90°-95° F. even when the nursery temperature reaches 100°-105° F.

The humidification capacity of the unit should be adequate to maintain a relative humidity of as high as 85%-100% under any conditions, especially including conditions when oxygen is in use within the occupant space, and at levels down to 40%-50% relative humidity. The humidity control should be sensitive enough to maintain the desired humidity within about $\pm 7\frac{1}{2}\%$.

I claim:

1. In an infant incubator having a base and a cover member therefor, the cover member being mounted for motion between a closed position in which it rests on the base and forms an enclosed occupant space and an open position in which it is displaced from the base, the base including a housing member and a deck, the deck including an infant receiving mattress, the housing member having a plurality of upwardly open depressions in the upper surface thereof, the depressions forming chambers through which air may pass and in which the variable, temperature, moisture content, and oxygen content may be adjusted to predetermined desired levels, passage means formed in the housing member providing intercommunication between said chambers, the deck being adapted to overlie the housing member and enclose the top of each of said chambers, a delivery member having a delivery passage therein through which the air flows from said chambers below the deck to the occupant space above the deck, and a fan for effecting forced air circulation through said chambers, the delivery member, and the occupant space, said chambers including a cooling chamber and a humidifying chamber as the last chambers in the direction of air flow before the delivery member, said cooling chamber and said humidifying chamber being arranged in the air flow circuit in parallel, the delivery member being adjustable to a predetermined air-flow condition from an extreme condition of maximum exposure to flow from the cooling chamber and minimum exposure to flow from the humidifying chamber to an opposite extreme condition of maximum exposure to flow from the humidifying chamber and minimum exposure to flow from the cooling chamber, and control means for adjusting the delivery member to that air-flow condition which will produce a flow to the occupant space of cooled air and humidified air in desired proportions.

2. A construction according to claim 1 in which the humidifying chamber and the cooling chamber comprise side-by-side depressions in the base member separated by a wall, the deck includes two apertures arranged in side-by-side relation with one aperture on each side of said wall, and the delivery member is shiftable over the apertures, whereby to deliver a desired proportion of air from each of said humidifying and cooling chambers.

3. A construction according to claim 2 in which the delivery member comprises a support member and an upstanding hollow body member, the support member including an aperture in communication with the hollow body member.

4. A construction according to claim 3 in which the position of the delivery member is determined by control means comprising, a manually rotatable control member outside of the cover member and mounted for rotation with a shaft passing through the cover member, a control finger mounted on said shaft inside of the cover member, the control finger being mounted for rotation with said shaft in a plane parallel to the plane of the shifting movement of the delivery member, abutment means on the delivery member, the manual control member, shaft and control finger assembly being movable axially between a position in which the finger abuts the abutment means during rotation and a position in which the finger swings clear of the abutment means, the assembly being biased toward said last-mentioned position, whereby, upon man-

ual axial movement of the assembly in direction to engage the control finger with the abutment means, shifting movement of the delivery member can be effected upon manual rotation of the control member.

5. A construction according to claim 1 in which the housing member is formed as a unitary casting, the plurality of upwardly open depressions being substantially smooth-walled with the intersections of adjacent walls being rounded and filleted, whereby to provide for ready access to and cleaning of the chambers through which air passes to the occupant space.

15 6. A construction according to claim 1 and further including a gasket positioned to serve as a seat for said cover member when the cover member is in the closed position, the gasket being formed as a single loop in the shape of the mating surfaces of the cover member and base, the gasket being smooth-surfaced and readily removable, whereby to provide for ease of cleaning of the gasket and the mating surfaces of the cover member and base.

20 7. A construction according to claim 6 in which the gasket is of flattened tubular section, whereby to provide a sealed-in air pocket.

25 8. A construction according to claim 1 in which said chambers include a mixing chamber into which return air from the occupant space, new air from an outside source and oxygen may be introduced, the construction further including filter means for the new air introduced into the mixing chamber, said filter means comprising a 30 housing and a cap structure, the cap structure including a continuous peripheral surface adapted to mate with a corresponding seat surface on the filter housing, a piece of filter material adapted for insertion between the filter housing and cap structure with the peripheral edge portion squeezed between the mating surfaces of the filter housing and cap structure, clamp means adapted to exert a force on the cap structure in direction to increase the squeezing of the periphery of the filter material, and an access conduit interconnecting the filter housing and the mixing chamber, the filter material being adapted to remove substantially 100% of particles down to 0.5 micron from air passing therethrough.

35 9. A construction according to claim 8 in which the access conduit is adapted to deliver air directly into the impeller housing through an input aperture in the wall of the housing, the input aperture being of a size larger than the access conduit to provide an annular space around the access conduit through which air from the mixing chamber may enter the impeller housing.

40 10. A construction according to claim 1 and further including a combined input port, level indicator and drain for the humidifying chamber comprising a pipe communicating with the humidifying chamber adjacent the bottom thereof and protruding outwardly outside of the incubator base, and a tubular member open at one end and closed at the other, said tubular member being mounted at the closed end for rotation on the end of said pipe, the interior of the tubular member and the interior of said pipe being in communication, the tubular member being rotatable between an up position in which the tubular member extends upwardly from the pipe and a down position in which it extends downwardly from the pipe, the tubular member in the up position providing an input port for the filling of the humidifying chamber and for 45 the indication of the water level in said chamber, and the tubular member in the down position providing a drain for the humidifying chamber.

50 11. In an infant incubator having an enclosed occupant space, the improvement comprising a base member including a housing member formed as a unitary casting having a plurality of depressions therein, the depressions all being open in a given direction and all being accessible from that direction, the depressions forming chambers through which air may pass and in which the vari- 55 ables, temperature, moisture content and oxygen content

may be adjusted to predetermined desired levels, means in said chambers for adjusting said variables, closure means adapted for assembly with the housing member from said given direction, the closure means being adapted to close each of said chambers, the closure means being yieldingly urged by a first force toward closed position but being movable from said position by the application of a second force opposing and greater than said first force, the plurality of depressions being substantially smooth-walled with filleted and rounded wall intersections and edges, whereby to provide for ease of access to, and to facilitate cleaning of all of the chambers.

12. A construction according to claim 11 in which the plurality of upwardly open depressions comprise chambers through which air may flow on its way to the occupant space of the incubator, the chambers including a mixing chamber, a heating chamber, a cooling chamber and a humidifying chamber, the cooling chamber and the humidifying chamber being arranged in the air flow circuit in parallel as the last chambers, in the direction of air flow, before the air is delivered to the occupant space, means for proportioning the air flowing through the cooling and humidifying chambers and providing a flow to the occupant space of cooled air and humidified air in desired proportions, the mixing chamber including a fan having an impeller for establishing forced air circulation through the chambers and occupant space, a motor for driving said impeller, the mixing chamber including an impeller housing as an integral part of the cast wall thereof, the motor and impeller being mounted on a removable motor board, whereby to provide for ease of access to and cleaning of the interior of the impeller housing.

13. A construction according to claim 12, in which the heating chamber includes an electric heater element and the mixing chamber includes a thermostat, the walls of the heating and mixing chambers including apertures through which the heater element and thermostats may protrude into the interior of the chambers, the heater element and thermostat being mounted on said motor board, whereby to provide for removal of the motor, impeller, heater element, and thermostat as a unit.

14. A construction according to claim 13 in which the deck includes an exit aperture to permit air to flow from the occupant space to the mixing chamber, the deck including downwardly extending shield means arranged around said exit aperture, the shield means being positioned to surround the thermostat when the deck is in position on the housing member.

15. In an infant incubator having a base and a cover member therefor, the cover member being mounted for motion between a closed position in which it rests on the base and forms an enclosed occupant space and an open position in which it is displaced from the base, the base including a housing member and a deck, the deck including an infant receiving mattress, the housing member having a plurality of upwardly open depressions in the upper surface thereof, the depressions forming chambers through which air may pass and in which the variables, temperature, moisture content, and oxygen content, may be adjusted to predetermined desired levels, passage means formed in the housing member providing intercommunication between said chambers, the deck being adapted to overlie the housing member and enclose the top of each of said chambers, a delivery member having a delivery passage therein through which the air flows from said chambers below the deck to the occupant space above the deck, and a fan for effecting forced air circulation through said chambers, the delivery member, and the occupant space, said chambers including a dry-air chamber and a humidifying chamber as the last chambers in the direction of air flow before the delivery member, said dry-air chamber and said humidifying chamber being arranged in the air flow circuit in parallel, the de-

livery member being adjustable to a predetermined air-flow condition from an extreme condition of maximum exposure to flow from the dry-air chamber and minimum exposure to flow from the humidifying chamber to an opposite extreme condition of maximum exposure to flow from a humidifying chamber and minimum exposure to flow from the dry-air chamber, and control means for adjusting the delivery member to that air-flow condition which will produce a flow to the occupant space of dry air and humidified air in desired proportions.

16. A construction according to claim 15 in which the delivery member comprises a support member and an upstanding hollow body member, the support member including an aperture in communication with the hollow body member, the deck of the incubator including two apertures in side-by-side relation, one aperture communicating with the dry-air chamber and the other aperture communicating with the humidifying chamber.

17. A construction according to claim 16 in which the delivery member is shiftable to any desired position from a position in which the delivery passage communicates with said humidifying chamber only, while the support member occludes communication with the dry-air chamber to a position in which the delivery passage communicates with substantially only the dry-air chamber while remaining in partial communication with the humidifying chamber.

18. A construction according to claim 16 in which the upstanding hollow body member includes a plurality of opposed spaced baffles adapted to mix the air during passage through the delivery member, the flow area past each baffle within the delivery member being at least as great as the flow area in communication with the delivery passage from both the dry-air and the humidifying chambers.

19. A construction according to claim 16 in which the upstanding hollow body member includes an air delivery passage through which the stream of air flows into the occupant space, the incubator including a cross plate adjacent the delivery member, said cross plate being adapted to limit the motion of an infant in the incubator toward the delivery member, the upper edge of the cross plate being positioned above the mattress a distance at least as great as the distance from the mattress to the midpoint of the head of the infant in the incubator, the air delivery passage being positioned above the mattress a distance at least as great as the distance from the mattress to the upper edge of the cross plate but not greater than one-half the distance from the mattress to the ceiling of the occupant space.

20. A construction according to claim 19 in which the air delivery passage is positioned to deliver a stream of air in an upwardly direction, the position of the air delivery passage being selected so that there results a thorough mixing of the incoming air with the air in the occupant space while maintaining an air flow in the region from the mattress up to about 6" above the mattress of not more than about 25 ft./min.

21. In an infant incubator having an enclosed occupant space; a housing member having a plurality of depressions therein; the depressions all being open in a given direction and all being accessible from that direction; the depressions forming chambers through which air may pass and in which the variables, temperature, moisture content, and oxygen content may be adjusted to predetermined desired levels; a closure member adapted for assembly with the housing member from said given direction; the closure member being adapted to enclose each of said chambers; passage means providing intercommunication between said chambers; delivery means through which air flows from said chambers to the occupant space; said chambers including a dry-air chamber and a humidifying chamber as the last chambers in the direction of air flow before the delivery means; said dry-air chamber and said humidifying chamber being arranged in the air-flow circuit in parallel; the delivery means being

adjustable to a predetermined air-flow condition from an extreme condition of maximum exposure to flow from the dry-air chamber and minimum exposure to flow from the humidifying chamber to an opposite extreme condition of maximum exposure to flow from the humidifying chamber and minimum exposure to flow from the dry-air chamber; and control means for adjusting the delivery means to that air-flow condition which will produce a flow to the occupant space of dry air and humidified air in desired proportions.

22. A construction according to claim 21 in which the housing member is formed as a unitary casting, the plurality of depressions being substantially smooth-walled with filleted and rounded wall intersections and edges, whereby to facilitate cleaning of the chambers.

23. In an infant incubator having an enclosed occupant space; a housing member having a plurality of chambers through which air may pass and in which the variables, temperature, moisture content, and oxygen content may be adjusted to predetermined desired levels; delivery means through which air flows from said chambers to the occupant space; a fan for effecting forced air circulation through said chambers, delivery means, and occupant space; said chambers including a dry-air chamber and a humidifying chamber as the last chambers in the direction of air flow before the delivery means; said dry-air chamber and said humidifying chamber being arranged in the air-flow circuit in parallel; the delivery means being adjustable to a predetermined air-flow condition from an extreme condition of maximum exposure to flow from the dry-air chamber and minimum exposure to flow from the humidifying chamber to an opposite extreme condition of maximum exposure to flow from the humidifying chamber and minimum exposure to flow from the dry-air chamber; and control means for adjusting the delivery means to that air-flow condition which will produce a flow to the occupant space of dry air and humidified air in desired proportions.

24. A construction according to claim 23 in which said chambers include a mixing chamber into which new air from an outside source may be introduced, the construction further including filter means for the new air, said filter means comprising a filter housing and a cap structure, the cap structure including a continuous peripheral surface adapted to mate with a corresponding seat surface on the filter housing, a piece of filter material adapted for insertion between the filter housing and cap structure with the peripheral edge portion squeezed between the mating surfaces of the filter housing and cap structure, clamp means adapted to exert a force in direction to increase the squeezing of the periphery of the filter material, and conduit means interconnecting the filter housing and the mixing chamber.

25. A construction according to claim 23 in which the occupant space is enclosed by a base member and a cover member therefor, the cover member being mounted for motion between a closed position in which it rests on the base and an open position in which it is displaced from the base, the construction further including a gasket positioned to serve as a seat for said cover member when the cover member is in the closed position, the gasket being formed as a single loop in the shape of the mating surfaces of the cover member and base member, the gasket being smooth-surfaced and readily removable, whereby to provide for ease of cleaning of the gasket and the mating surfaces of the cover member and base member.

26. A construction according to claim 23 in which the humidifying chamber and the dry-air chamber are separated from each other by a partition and are both separated from the delivery means by wall means, said wall means including two apertures arranged in side-by-side relation with one aperture on each side of said partition, the delivery means including a hollow body member shiftable over said apertures, whereby to provide for the

flow to the delivery means of a desired proportion of air from each of said humidifying and dry-air chambers.

27. A construction according to claim 26 in which the body member of the delivery means is shiftable to any desired position from a position in which the body member communicates with said humidifying chamber only, to a position in which the body member communicates with substantially only the dry-air chamber, while remaining in partial communication with the humidifying chamber.

28. A construction according to claim 26 in which the hollow body member includes a plurality of opposed spaced baffles adapted to mix the air during passage thereof through the delivery means, the flow area past each baffle within the hollow body member being at least as great as the flow area in communication with the hollow body member from both the dry-air and humidifying chambers.

29. A construction according to claim 26 in which the position of the body member is determined by control means comprising, a manually rotatable control member outside of the occupant space and mounted for rotation with a shaft passing into the occupant space, a control finger mounted on said shaft inside of the occupant space, the control finger being mounted for rotation with said shaft in a plane parallel to the plane of the shifting movement of the body member, abutment means on the body member, the assembly of manual control member, shaft and control finger being movable axially of the shaft between a position in which the finger abuts the abutment means during rotation of the finger and a position in which the finger swings clear of the abutment means, the assembly being biased toward said last-mentioned position, whereby, upon manual axial movement of the assembly in direction to engage the control finger with the abutment means, shifting movement of the body member can be effected upon manual rotation of the control member.

30. A construction according to claim 26 in which the delivery means includes an air-delivery passage through which the stream of air flows into the occupant space, the incubator including a cross plate adjacent the delivery means, said cross plate being adapted to limit the motion of an infant in the incubator toward the delivery means, the upper edge of the cross plate being positioned above the infant supporting surface of the incubator a distance at least as great as the distance from the infant supporting surface to the mid-point of the head of the infant in the incubator, said air-delivery passage being positioned above the infant supporting surface a distance at least as great as the distance from the infant supporting surface to the upper edge of the cross plate but not greater than one-half the distance from the infant supporting surface to the ceiling of the occupant space.

31. A construction according to claim 30 in which the air-delivery passage is positioned to deliver a stream of air in an upwardly direction, the position of the air-delivery passage being selected so that there results a thorough mixing of the incoming air with the air in the occupant space while maintaining an air flow in the region from the infant supporting surface up to about six inches above said surface of not more than about twenty-five feet per minute.

32. In an infant incubator having an enclosed occupant space; a housing member having a plurality of chambers through which air may pass and in which the variables, temperature, moisture content, and oxygen content may be adjusted to predetermined desired levels; delivery means through which air flows from said chambers to the occupant space; said chambers including a dry-air chamber and a humidifying chamber as the last chambers in the direction of air flow before the delivery means; said dry-air chamber and said humidifying chamber being arranged in the air-flow circuit in parallel; the delivery means being adjustable to a predetermined air-flow condi-

tion from an extreme condition of maximum exposure to flow from the dry-air chamber and minimum exposure to flow from the humidifying chamber to an opposite extreme condition of maximum exposure to flow from the humidifying chamber and minimum exposure to flow from the dry-air chamber; and control means for adjusting the delivery means to that air-flow condition which will produce a flow to the occupant space of dry air and humidified air in desired proportions.
